ABSTRACT OF THE DISCLOSURE

The broadband high-Q antenna system employs a feed forward circuit in combination with a feedback circuit to tune a high-Q antenna in accordance with the instantaneous frequency of a transmitted signal. The feed forward circuit changes the reactance of the antenna in response to a control signal from a transmitter while the feedback circuit insures that the passband of the high-Q antenna is centered about the transmitter frequency.

BACKGROUND OF THE INVENTION

This invention relates to antenna systems, in particular to a broadband high-Q antenna system useful in a system for transmitting frequency shift keying (FSK) and phase shift keying (PSK) data at a signaling rate higher than the antenna bandwidth.

The bandwidth and transmission speeds over radio communication channels are presently limited by the high-Q antenna system used. As is well known, if the bandwidth of a transmitted signal is considerably greater than the antenna bandwidth, the output transmitted power is greatly reduced. However, if the antenna is tuned in accordance with the instantaneous frequency of the transmitted signal, no reduction in radiated power occurs. This tuning is known as synchronous tuning. Basically, there are two methods of achieving synchronous tuning. The first method is to switch a reactance into the antenna circuit. This instantaneously changes the resonance frequency of the antenna. To avoid generation of spurious frequency components, the switching must occur at the proper instants of time. The second method of synchronous tuning is to use a nonlinear reactance element (capacitor or inductor) in the antenna circuit. Since the resonance frequency depends on the average reactance of the nonlinear element, which, in turn, can be made to vary by means of a control signal, continuous tuning of the antenna resonance frequency can be achieved.

For the first method, highly efficient switching techniques have been proposed. These techniques make it quite possible to switch instantaneously from one frequency to another so that a maximum data rate equal to half the transmitter frequency is possible. This high switching speed, however, may be a disadvantage if the desired data rate is much less than the maximum data rate achievable. Since fast switching tends to produce a square-wave, frequency-modulated waveform, a wide frequency spectrum is generated. This wide frequency spectrum is undesirable because of interchannel interference. Furthermore, a square-wave modulated waveform does not enhance the signal detectability of any significance beyond that of a sinusoidal modulated waveform. In general, therefore, it may be concluded that fast switching is undesirable for almost all VLF communication systems. Another reason for making this method of synchronous tuning impractical is the very high power rating required of the switch.

The nonlinear reactance system permits continuous transitions from one frequency to another. Thus, transitions that generate the minimum amounts of unwanted sidebands can be implemented. The main disadvantage of

2

this system is the generation of harmonics of the transmitter frequency. For a high-Q antenna system, these harmonics may be sufficiently small so that they do not cause any serious interference problem. However, the use of a balanced nonlinear reactance circuit makes possible cancellation of these harmonics. While the nonlinear reactance system requires a large control power, the controlling element is reactive, and the real part of the control power required depends only upon the losses in the control circuit. A broadband high-Q antenna system according to the present invention employs a highly efficient switching circuit to change the average reactance.

SUMMARY OF THE INVENTION

15 Briefly, the system according to the present invention employs, in combination, a feedback circuit and a feed forward circuit to tune the antenna in accordance with the instantaneous frequency of an information signal. The antenna circuit includes two reactance means, one of which is connected to the feed forward circuit and the other of which is connected to the feedback loop. In response to a transmitter trigger signal, which indicates that the frequency (or phase) of the information signal, typically an RF signal, is about to change, the feed forward circuit changes the value of its associated reactance in the antenna circuit, thus tuning the antenna to the new frequency. The feedback loop then senses the phase difference between the antenna current and the RF transmitter signal and generates a control signal which varies the reactance of the second reactance element to fine tune the high-Q antenna to the center frequency of the RF transmitter signal.

DESCRIPTION OF THE DRAWINGS

35 The construction and operation of the antenna system according to the invention will be more fully understood from the following detailed description taken in conjunction with the accompanying drawings in which:

40 FIG. 1 is a block diagram of an embodiment of the invention;

FIG. 2 is a more detailed diagram of the embodiment of FIG. 1;

FIG. 3 is a schematic representation of one species of a switching circuit employed in the embodiment shown in FIG. 2;

FIG. 4 is a representation of voltage and current wave-shapes useful in explaining the operation of the switching circuit of FIG. 3;

50 FIG. 5 is a schematic representation of a second species of a switching circuit which may be employed in the embodiment shown in FIG. 2;

FIG. 6 is a representation of voltage and current wave-shapes useful in explaining the operation of the switching circuit of FIG. 5;

55 FIG. 7 is a schematic representation of a logic unit employed in the embodiment of FIG. 2; and

FIG. 8 is a representation of voltage and current wave-shapes useful in explaining the operation of the logic unit of FIG. 7.

DETAILED DESCRIPTION

Referring to FIG. 1; a radio frequency (RF) output signal on line 10 of a transmitter 12, typically an FSK or PSK type, is directed to both a high Q antenna 14 and to a feedback circuit 16. Line 18 connects an input signal from the antenna 14 to the feedback circuit 16. The output signal of the feedback circuit 16 in turn is connected to the antenna 14 via line 20. A trigger signal from the transmitter 12 is connected via line 24 to a feed forward circuit 22, the output of which is connected to the antenna 14.

In operation, the RF output signal from the transmitter

12 is directed simultaneously to the antenna 14 and to the feedback circuit 16. A sample of the resultant signal, established in the antenna 14 by the transmitter 12, is directed to the feedback circuit 16 via line 18. The sample is compared to the RF transmitter output signal and an error signal is generated when there is phase difference between the two signals. The error signal thus generated is directed via line 20 to vary a reactance element of the antenna such that the Q of the antenna is centered about the frequency of the RF output signal of the transmitter 12.

In an FSK system, when a change in the frequency of the transmitter output signal occurs (or in a PSK system, a change in phase), a trigger signal is directed to the feed forward circuit 22 from the transmitter 12 via line 24. In response to the trigger signal, the feed forward circuit 22 generates a signal which changes a second reactance element of the antenna 14 such that the center frequency of the antenna is approximately centered about the center frequency of the transmitter RF output signal. The feedback circuit 16 then functions to insure tracking between the antenna center frequency and the transmitted signal and to compensate for small changes and unbalanced conditions in the antenna 14 and feed forward circuitry 22.

FIG. 2 is a more detailed diagram of the embodiment shown in FIG. 1. The feedback circuit 16 includes a phase detector 30, typically a standard zero-crossing phase detector, having a first input connection to the transmitter 12 via line 10 and a second input connection to the antenna 14 via line 18. The output of the phase detector 30 is connected to a power amplifier 32, the output signal of which is connected to the control side of a reactance element L_1 , typically two series connected saturable reactors, each having an output winding and a control winding.

The feed forward circuit 22 includes a logic circuit 34, to be discussed hereinafter, which receives a trigger input signal via line 24 from the transmitter 12. The output signal of the logic unit 34 is connected to a switching circuit 35, also to be discussed in detail hereinafter, the output signal of which is connected to the control side of a second reactance element L_2 , typically two series connected saturable reactors.

A typical circuit for the antenna 14 includes the tuning inductor L_3 which is connected in series with the antenna represented by a capacitor C_1 , resistor R_1 , the output windings of the saturable reactors L_1 and L_2 and resistance R_2 . The common junction of resistance R_2 and saturable reactors L_1 is connected to the phase detector 30 by line 18. The transmitter 12 is connected to the antenna 14 via a tap on the inductor L_3 .

In operation, a trigger signal is directed from transmitter 12 to logic unit 34 via line 24 when a change in the transmitter frequency in an FSK system or when a change in phase in a PSK system occurs. In response to the trigger signal, the logic unit 34 generates and directs a sequence of signals to the switching circuit 35 which in turn performs the actual change in the average reactance of the saturable reactor L_2 . The phase detector 30 compares the phase of transmitter output voltage to the phase of the antenna current and generates a D.C. error signal proportional to the phase difference between the two signals. This D.C. error signal is then amplified by the power amplifier 32 and directed to the control windings of the saturable reactor L_1 to adjust the inductance L_1 in such a direction as to eliminate the phase difference between the transmitter signal and the antenna current, thus insuring that the passband of the antenna 14 is centered about the transmitted frequency.

FIGS. 3 and 5 are schematic representations of switching circuits which may be employed in the system of FIG. 2. The particular species of switching circuit shown in FIG. 3 is employed in an FSK system while that of FIG. 5 is employed in a PSK system. Referring to FIG. 3, a first low voltage power supply 40 is connected in parallel with a series combination of a switch S_1 , typically a relay

or semiconductor gate controlled by a control signal from logic unit 34, and an inductor L_{30} . A capacitor C_{30} is connected in parallel with the inductor L_{30} and with the series combination of a switch S_2 and a capacitor C_{32} . Connected in parallel with capacitor C_{32} is the control winding of the antenna saturable reactor L_2 and the series combination of a switch S_3 and a second low voltage power supply 42.

The waveshapes shown in FIG. 4 will be employed to explain the operation of the switching circuit of FIG. 3. Initially, switch S_1 is closed and switches S_2 and S_3 are open and the antenna is tuned to a frequency designated as f_1 . The current i flows through the inductor L_{30} and is given by the expression

$$i_1 = \frac{V}{R_{L2}} \quad (1)$$

where V is the voltage of the low voltage power supply 40 and R_{L2} is the internal resistance of the inductor L_{30} . When a change in frequency occurs, for example, changing from frequency f_1 to f_2 , a control signal is generated in the logic unit 34 which opens switch S_1 and closes switch S_2 . The time occurrence of this event is indicated as t_0 in FIG. 4. When the capacitor voltage approaches zero at time t_1 , the current i_1 in inductor L_{30} is completely transferred to saturable reactor as current i_2 and thereby changing the inductance in the antenna circuit from a high value to a low value. Thus, the antenna is tuned to the instantaneous frequency of the transmitter RF output signal.

Just prior to t_1 , when the capacitor voltage is equal to the supply voltage, V , a control signal is generated in logic unit 34 that opens switch S_2 and closes switch S_3 connecting power supply 42 to the circuit. If the switching circuit were lossless, two power supplies would not be required. However, since transfer of all of the current i_1 in inductor L_{30} to saturable inductor L_2 is not possible because of the I^2R loss, a second power supply 42 is switched into the circuit by closure of switch S_3 . Note that all the elements in the switching circuit are reactive and, therefore, the power supplies need only supply the relatively small amount of power dissipated in the internal resistance of the circuit components.

The time required to effectuate a transfer between frequency f_1 and f_2 is

$$T = t_0 - t_1 = 2\sqrt{(L_{30} + L_2)(C_{30} + C_{32})} \quad (2)$$

so that the maximum data rate becomes

$$f_p = \frac{1}{T} = \frac{1}{2\sqrt{(L_{30} + L_2)(C_{30} + C_{32})}} \quad (3)$$

The switching circuit of FIG. 3 is symmetrical so that when a frequency change from f_2 and f_1 occurs the sequence of the switching operation is reversed.

A species of the switching circuit which can be employed in a PSK system is shown in FIG. 5. A high voltage power supply 58 is connected to a series combination of a switch S_4 and a capacitor C_{60} . Connected in parallel with capacitor C_{60} is a series combination of a switch S_5 , the control windings of the antenna saturable reactor L_2 and a capacitor C_{62} . Connected in parallel with capacitor C_{62} is a series combination of a switch S_6 and a second high voltage power supply 64.

The voltage and current waveshapes of FIG. 6 will be used to explain the operation of the switching circuit of FIG. 5. Initially, the switches S_5 and S_6 are open and S_4 is closed, impressing the voltage V of the high voltage supply 58 across capacitor C_{60} . At time t_0 , control signals from logic unit 34 are generated to open switch S_4 and close switch S_5 producing the voltage and current waveshapes shown in FIG. 6. The voltage e_{C60} is transferred from capacitor C_{60} to capacitor C_{62} causing a current i to flow through the control winding of the antenna saturable reactor L_2 . At time t_1 , the charge on capacitor C_{60} is completely transferred to capacitor C_{62} , and a signal is received from logic unit 34 to open switch S_5 and close S_6 .

The desired phase change is obtained by varying the

frequency of the transmitter RF output signal during the time interval from t_0 to t_1 in accordance with the control current i . (One method of changing phase in a typical PSK system is to change the frequency from f_1 to f_2 and back to f_1 such that when the frequency returns to f_1 it has been shifted in phase with respect to the phase of f_1 prior to the transition.) The control current i insures that the antenna is tuned to the transmitter frequency throughout the phase transition. The switching time

$$T = t_1 - t_0 = \sqrt{2CL_2} \quad (4) \quad 10$$

and, therefore, the maximum data rate, f_p , becomes

$$f_p = \frac{1}{\sqrt{2CL_2}} \quad (5) \quad 15$$

The phase circuit of FIG. 5 is symmetrical, therefore, when a phase change from phase 2 to phase 1 occurs the sequence of the switching operation is reversed.

Referring now to FIG. 7, a typical logic unit 34 employed in the embodiment of FIG. 2 is shown. The logic unit 34 includes an input connection 71 which is connected to a line 70, a complementary circuit 72, and a delay, τ_1 . Complementary circuit 72 is typically a flip-flop and delay τ_1 is typically a one-shot multivibrator. Line 70 is connected to a control line 90. The output of flip-flop 72 and output line 74 from delay τ_1 are connected to a second control line 92. A second output line 76 from delay τ_1 is connected to a third control line 94. The input of delay τ_2 is also connected to the first output of delay τ_1 , via line 78. The first output of delay τ_2 is connected to the control line 94 and to the input of a delay τ_3 via lines 80 and 82, respectively. The second output of the delay τ_2 is connected to the control line 92 via line 84. First and second outputs of delay τ_3 are connected to the control lines 92 and 90 via lines 86 and 88, respectively.

The operation of logic unit 34 will be explained in conjunction with the current and voltage waveshapes of FIG. 8 and the switching circuit of FIG. 3. In response to a trigger signal from transmitter 12, switch S_1 , which is initially closed, is opened as indicated by the "1" on line 70. Simultaneously with the opening of switch 1, the trigger signal activates complementary flip-flop 72 (which in turn supplies a control signal on line 92 to close switch S_2) and starts the delay τ_1 . These events occur at time t_0 as indicated in FIG. 8. The current i_1 in L_{30} is transferred to L_2 as shown in FIG. 8. At time t_1 , delay τ_1 not only generates a first output signal which opens switch S_2 via control line 92 and starts delay τ_2 but also generates a second output signal which closes the switch S_3 via control line 94. At this point, t_1 , the transmitter is transmitting frequency f_2 and the antenna is tuned to that frequency. At time t_2 , delay τ_2 not only generates a first output signal which opens switch S_3 via control line 94 and initiates delay τ_3 via line 82 but also generates a second output signal which closes switch S_2 via control line 92. The current i_2 stored in L_2 is then transferred back to inductor L_{30} as indicated by the wave-shapes of FIG. 8. At time t_3 , delay τ_3 produces a first output signal to open switch S_2 via control line 92 and a second output signal to close switch S_1 via control line 90. Note that delay τ_1 is equal to delay τ_3 and is fixed by the components in the switching circuit. However, delay time τ_2 can be any value greater than delay time τ_1 .

While a number of modifications to the broadband high-Q antenna system have been suggested, it will be apparent that many variations may be made by one skilled in the art without departing from the spirit of the invention. It is, therefore, intended that the invention not be limited to specifics of the foregoing description but rather to embrace the full scope of the following claims.

What is claimed is:

1. A broadband high-Q antenna system comprising:
transmitter means operative to generate an information signal and a trigger signal, said trigger signal being

generated when a predetermined change in the information signal takes place;
an antenna circuit including first and second reactance means, each reactance means having a pair of series-connected nonlinear saturable reactors, each of said saturable reactors having a control winding and an output winding;

a feed forward circuit connected to said transmitter means and to said first reactance means and including a logic means operative in response to the trigger signal from said transmitter means to generate a sequence of switching signals, and a switch circuit including

a first low voltage power supply having first and second terminals,

first switching means having a control line connected to said logic unit and having a first and second terminal, said first terminal being connected to the first terminal of said first low voltage power supply,

inductance means having one end connected to the second terminal of said first low voltage power supply and the other end connected to the second terminal of said first switching means,

said first switching means being operative in response to a switching signal from said logic unit to transfer energy from said first low voltage power supply to said inductance means,

a first capacitor having one end connected to the second terminal of said first low voltage power supply and having the other end connected to the common connection of said first switching means and said inductance means,

second switching means having a control line connected to said logic unit and having first and second terminals, said first terminal being connected to the common connection of said first switching means, said inductance means and said first capacitor,

a second capacitor having one end connected to the second terminal of said first low voltage power supply and the other end connected to the second terminal of said second switching means and to said first terminal of the control circuit of said first reactance means,

said second switching means being operative in response to a switching signal from said logic unit to transfer energy from said first capacitor to said second capacitor,

third switching means having a control line connected to said logic unit and having first and second terminals,

said first terminal being connected to the common connection of said second switching means, said second capacitor and the control circuit of said first reactance means,

a second low voltage power supply having a first terminal connected to the second terminal of said third switching means and having a second terminal connected to both the second terminal of the control circuit of said first reactance means and the second terminal of said first low voltage power supply,

said third switching means being operative in response to a switching signal from said logic unit to transfer energy from said second low voltage power supply to the second capacitor; and

a feedback circuit connected to said transmitter means

and to the second reactance means of said antenna, said feedback circuit being operative to sense the phase difference between the information signal from said transmitter means and the signal in said antenna and to generate a control signal in response to said phase difference to vary the reactance value of said second reactance means. 5

2. A broadband high-Q antenna system comprising: transmitter means operative to generate an information signal and a trigger signal, said trigger signal being generated when a predetermined change in the information signal takes place; an antenna circuit including first and second reactance means, each having a pair of series-connected nonlinear saturable reactors, each of said saturable reactors having a control winding and an output winding; a feed forward circuit connected to said transmitter means and to said first reactance means and including 15 a logic means operative in response to the trigger signal from said transmitter means to generate a sequence of switching signals, and a switch circuit including 20 a first high voltage supply having first and second terminals, a first switching means having a control line connected to said logic unit and having first and second terminals, said first terminal being connected to the first terminal of said first high voltage supply, a first capacitor having one end connected to the second terminal of said first high voltage power supply and having the other end connected to the second terminal of said first switching means, 25 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of said first switching means and said first capacitor and the second terminal of said second switching means being connected to the first terminal of the control winding of said first reactance means, 30 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of said first switching means and said first capacitor and the second terminal of said second switching means being connected to the first terminal of the control winding of said first reactance means, 35 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 40 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 45 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 50 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 55 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 60 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 65 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 70 said first switching means being operative in response to a switching signal from said logic unit to transfer energy from said first high voltage supply to said first capacitor, second switching means having a control line connected to said logic unit and having first second terminals, the first terminal of said second switching means being connected to the common connection of the second terminal of the control winding of said first reactance means and said second capacitor, the second terminal of said second switching means being connected to the first terminal of the control winding of said first reactance means, 75

being connected to the second terminal of said third switching means, and said third switching means being operative in response to a switching signal from said logic unit to transfer energy from said high voltage supply to said second capacitor; and

- a feedback circuit connected to said transmitter means and to the second reactance means of said antenna, said feedback circuit being operative to sense the phase difference between the information signal from said transmitter means and the signal in said antenna and to generate a control signal in response to said phase difference to vary the reactance value of said second reactance means. 3. A broadband high-Q antenna system according to claim 2 wherein the logic unit comprises: an input terminal connected to said transmitter means and operative to receive said trigger signal; a plurality of output terminals; a first connection means connected between said input terminal and a first terminal of said plurality of output terminals whereby said trigger signal constitutes a first switching signal; a flip-flop circuit having an input connected to said input terminal and an output connected to a second terminal of said plurality of output terminals, said flip-flop being operative in response to the trigger signal of said transmitter to generate a second switching signal; first delay means having an input connected to said input terminal and a first output connected to said second terminal and a second output connected to a third terminal of said plurality of output terminals, said first delay being operative in response to the trigger signal from said transmitter means to generate third and fourth switching signals at said second and third output terminals respectively; second delay means having an input connected to the first output of said first delay means and a first output connected to said third output terminal and a second output connected to said second output terminal, said second delay means being operative in response to said third switching signal to generate fifth and sixth switching signals at the second and third output terminals respectively of said plurality of output terminals; and third delay means having an input connected to the first output of said second delay means and having a first output connected to the second terminal of said plurality of output terminals and a second output connected to the first terminal of said plurality of output terminals, said third delay means being operative in response to said fifth switching signal to generate seventh and eighth switching signals at the second and first output terminals respectively of said plurality of output terminals. 4. A broadband high-Q antenna system according to claim 1 wherein the logic unit comprises: an input terminal connected to said transmitter means and operative to receive said trigger signal; a plurality of output terminals; a first connection means connection between said input terminal and a first terminal of said plurality of output terminals whereby said trigger signal constitutes a first switching signal; a flip-flop circuit having an input connected to said input terminal and an output connected to a second terminal of said plurality of output terminals, said flip-flop being operative in response to the trigger signal of said transmitter to generate a second switching signal; first delay means having an input connected to said input terminal and a first output connected to said second terminal and a second output connected to said second terminal and a second output connected to

a third terminal of said plurality of output terminals, said first delay being operative in response to the trigger signal from said transmitter means to generate third and fourth switching signals at said second and third output terminals respectively; 5
 second delay means having an input connected to the first output of said first delay means and a first output connected to said third output terminal and a second output connected to said second output terminal, said second delay means being operative in response to said third switching signal to generate fifth and sixth switching signals at the second and third output terminals respectively of said plurality of output terminals; and
 third delay means having an input connected to the 15 first output of said second delay means and having a first output connected to the second terminal of said plurality of output terminals and a second output connected to the first terminal of said plurality of

10

15

output terminals, said third delay means being operative in response to said fifth switching signal to generate seventh and eighth switching signals at the second and first output terminals respectively of said plurality of output terminals.
